[57] CLAIM

The ornamental design for a vehicle obstacle detector, as shown and described.

DESCRIPTION

FIG. 1 is a front perspective view of the vehicle obstacle detector showing new my design;

FIG. 2 is a rear perspective view thereof;

FIG. 3 is a top plan view thereof, the undisclosed opposite side being a mirror image; and,

FIG. 4 is a side elevational view thereof, the undisclosed opposite side being a mirror image.

The electrical cords have been shown broken away for ease of illustration and the broken line showing of FIG. 1 is a typical distance indicator.

FIG. 2

FIG. 3

FIG. 4
